UNITED STATES PATENT OFFICE.

JOHN TEMPLE, OF MIDDLETOWN, OHIO, ASSIGNOR TO TEMPLE, MILLS & STOUT.

WATER-WHEEL.

Specification of Letters Patent No. 22,902, dated February 8, 1859.

To all whom it may concern:

Be it known that I, JOHN TEMPLE, of Middletown, in the county of Butler and State of Ohio, have invented a new and useful Improvement in Water-Wheels; and I hereby declare the following to be a full and exact description of the same, reference being had to the accompanying drawings, making part of this specification, in which—

10 Figure 1 is a top view of the scroll chest. Fig. 2 is a view partly in axial section and partly in elevation. Fig. 3 is a horizontal section at $\alpha\alpha$ Fig. 2.

This is an improvement in what are 15 known as central discharge or vertical reaction wheels and the invention consists in a certain form and disposition of buckets whereby the forces of percussion reaction and gravity are made fully available.

20 The crown D of the wheel for a distance inward of about one half the radial depth of the buckets is a horizontal plane and thence to the back of the buckets is an inverted conic frustum of about 45° (or the 25 crown may curve inward and downward from the margin of the wheel to the back of the bucket). The buckets in all their horizontal sections, present a cyma reversa curve substantially such as shown in Fig. 3. The 30 front part (1) which receives the percussive force of the head being concave and the rear part (2) which receives the reacting force convex. The vertical sections present everywhere a cycloidal or circular arc trending 35 outward as it descends (see Fig. 2) so as to

present at the lower part of the discharge orifice an "apron" (3) adapted to receive and apply the gravitating force of the water. The recurring of the buckets (at 2) by enlarging the outlets prevents the gorging 40 of the passages under the diminished flow toward the discharge, incident to a central discharge wheel and prevents any pressure of water against the backs of the buckets.

I am aware that central discharge water 45 wheels having buckets recurved horizontally or in the plane of rotation have been long in use. I therefore do not claim such a mode of constructing wheels, but my invention involves important improvements on the 50 cyma-reversa bucket whereby I obtain in this class of wheels the advantages of percussion and reaction and in addition thereto a sufficient retention of the water to avail 55 the force of gravity.

I claim as new and of my invention herein—

The construction and arrangement in central discharge water wheels of buckets E, which have the described compound cyma 60 reversa and downward and outward curve whereby the water acts on the wheel by percussion reaction and gravitation and escapes freely without back action as set forth.

In testimony of which invention I here- 65 unto set my hand.

JOHN TEMPLE.
